PILE FABRIC FLOOR COVERING

Ernest R. Kuepfer, Cornwall-on-the-Hudson, N.Y.

Filed July 17, 1958, Ser. No. 51,814

Term of patent 14 years

(Cl. D92—4)

FIG. 1

Fig. 1 is a plan view of a pile fabric floor covering showing my new design;

Figure 2 is a fragmentary perspective view illustrating the relationship of the pile and ground yarn; and

I claim:

The ornamental design for a pile fabric floor covering, substantially as shown.
